UNITED STATES PATENT OFFICE.

BENJAMIN ABRAHAM, OF NEW YORK, N. Y.

NAPPED HAT:

SPECIFICATION forming part of Letters Patent No. 247,470, dated September 27, 1881.

Application filed August 22, 1881. (Model.)

To all whom it may concern:

Be it known that I, BENJAMIN ABRAHAM, of New York city, county and State of New York, have invented certain new and useful 5 Improvements in Napped Hats, of which the following is a specification.

My improvement relates to that class of hats, more especially for ladies' wear, which are finished with a napped or furry or woolly surface— 10 such as velvet, plush, or beaver—in which the fabric of the hat is covered with a raised nap or pile of fine hair or fibers; and my improvement consists in decorating or ornamenting the piled surface with strong hairs of a beardy 15 or bristly character, of a length greater than the pile, and of a distinguishing color, which hairs are inserted in the pile at numerous points throughout the same, thereby producing a contrast with the pile and imparting a sprightly 20 and ornamental effect to the hat, as hereinafter fully set forth.

Figure 1 of the drawings presents a perspective view of a napped hat finished according to my improvement, and Fig. 2 gives a cross- 25 section thereof.

In these views, *a* represents the sustaining fabric of the hat, which is preferably a true beaver felt, and *b* indicates the surface pile or nap, which may be raised thereon in the well-known manner in which beaver and silk hats 30 are produced. Instead of felt, however, the base fabric may consist of a frame of buckram, on which an external layer of plush may be pressed in the usual manner of making plush 35 hats, the pile or nap of the plush forming, in this case, the nap *b* of the hat. In lieu of plush, which is but a coarse kind of velvet, a true or fine velvet may be used, as will be readily understood, or any other material which gives a 40 napped or piled surface.

Napped hats as heretofore formed, particularly beaver nap, have usually too woolly and monotonous an appearance, and to correct this I decorate the pile at numerous points with 45 long hairs *c c*, which are preferably cemented at their roots into the roots of the nap, as well shown in Fig. 2. These hairs are preferably obtained from some fur-bearing animal—such as the fox, wolf, skunk, badger, or raccoon—

and they should be of a strong bristly or preferably beardy character, much longer than the fibers of the nap, and of a color to contrast therewith, so that when thus inserted in the pile they at once attract the eye, thereby giving it an animated appearance and effecting a 50 contrast which pleases the eye, removing the monotonous soft appearance of wooliness and imparting the lively appearance of animal fur, and thus rendering the hat much more sprightly 55 and dressy in appearance. The hairs of the fox are preferable to the others named, as they blend better with the woolly nap, the skunk and badger hairs being too bristly; and for black or brown hats the hair of the gray fox should be selected, while for light hats the hair 60 of the black or red fox may be employed. The hairs are preferably secured in the fur by dipping the root end in rubber cement and then twisting this end among the nap fibers, so as to cause the nap fibers to twist spirally around 65 the same and adhere, as shown in Fig. 2, thus securely retaining the hair, yet concealing its 70 origin among the nap fibers.

This improvement, which is more especially adapted for the better class of hats, adds but 75 slightly to their expense, and, as will be readily appreciated, imparts a finished animated tone to the hat, which materially adds to its value in dress and greatly increases its marketable 80 quality, thus presenting a good improvement in hats of the described kind.

What I claim is—

1. As a new article of manufacture, a napped hat finished with long animal hairs of a beardy or bristly nature inserted in and projecting from 85 the nap, substantially as herein set forth.

2. A hat formed of a base fabric of felt, or equivalent material, and an external layer of nap or pile with a series of beardy or bristly animal hairs inserted in and projecting from 90 the pile and of a greater length and different color therefrom, substantially as and for the purpose set forth.

BENJAMIN ABRAHAM.
